UNITED STATES PATENT OFFICE.

CHARLES SPIRO, OF NEW YORK, N. Y., ASSIGNOR TO FEDERAL ADDING MACHINE CORPORATION, OF NEW YORK, N. Y., A CORPORATION OF NEW JERSEY.

TYPEWRITER.

1,389,911.

Specification of Letters Patent. Patented Sept. 6, 1921.

Application filed March 1, 1920. Serial No. 362,248.

To all whom it may concern:

Be it known that I, CHARLES SPIRO, citizen of the United States, residing at New York, in the county of New York and State 5 of New York, have invented certain new and useful Improvements in Typewriters, of which the following is a specification.

This invention relates to a typewriter and particularly to a construction thereof comprising units adapted to be separately assembled and readily disposed in operative relation upon the main frame of a typewriter.

The invention has for an object to provide 15 a novel and improved construction wherein the frame base carries the key levers, space bar unit, and case shifting means and supports a fulcrum bar unit carrying type bars, sublevers, universal bail and ribbon vibrating and shifting members, together with a top plate supporting an escapement unit adapted to be disposed in operative relation to said bail and space bar unit.

A further object of the invention is to 25 provide an improved form of fulcrum bar unit for the sublevers detachably mounted upon the frame above the key levers in substantially the vertical plane of the typebar pivots upon a segment supported from said 30 fulcrum bar which is also provided with means for supporting and guiding a ribbon vibrating device in its case shifting movement.

Another object of the invention is to present 35 an improved unit for supporting members of a typewriter mechanism comprising a horizontal fulcrum bar having vertical supporting uprights for a segment carrying typebars, sublevers and universal bail and 40 a slide block upon its rear face, whereby the parts carried by this unit are adapted to be assembled in coöperative relation with case shift parts carried by the frame and an escapement unit upon the top plate of the 45 machine.

Other and further objects and advantages of the invention will be hereinafter set forth and the novel features thereof defined by the appended claims.

50 In the drawings—

Figure 1 is a vertical section;

Fig. 2 is a similar view on line 2—2 of

Fig. 1;

Fig. 3 is a horizontal section on line 3—3 55 of Fig. 2;

Fig. 4 is a similar view on line 4—4 of Fig. 1; and

Fig. 5 is a detail of the key lever link connection.

Like numerals refer to like parts in the 60 several figures of the drawings.

The numeral 10 designates the base or frame of the machine which may be of any desired construction or configuration, and is preferably provided with standards 11 at 65 each side thereof for supporting the top plate 12 which is detachably secured thereto for application after the parts within the frame have been assembled. This top plate unit carries the ribbon spools 13 and supports the carriage 14 at the rear thereof. To the under face of the plate 12 an escapement drum or housing 15 is secured and the driving pinion 16 therefrom meshes with a rack 17 upon the carriage. The carriage is also 70 provided with the case shifted platen 18 controlled through lever arms 19 which are connected by a shift rail 20 at the rear of the carriage. This rail may be depressed to shift the platen upward by any desired 75 means, such as the vertical shift rod 21 provided at its upper end with a swinging releasing arm 22 carrying a roller 23 which rides upon the upper face of the rail. The shift rod may be actuated by means which 80 will be hereinafter described.

For the purpose of supporting the assembled sublevers and typebars an improved form of unit is provided and comprises the horizontal fulcrum bar 25 having lugs 26 90 at its opposite ends detachably mounted upon coöperative lugs 27 from the inner face of the frame 10. At each end of this bar vertically disposed inwardly inclined uprights 28 are formed which support from 95 their upper ends the typebar segment 29. The rear face of this bar also carries a slide block 30 to support parts to be hereinafter described.

The segment 29 is provided with the pivot 100 rod 31 for the typebars 32 which are formed at their pivoted ends with an actuating slot 33 of the usual character. When the free ends of the typebars are at rest upon the support 34 carried by the front plate 48 105 mounted on cross plate 85 of the frame, the pivoted ends of the bars extend rearwardly beyond their pivot and are there connected to the sublevers 35 by means of pins 36 extending therefrom. For this purpose the 110

sublevers are pivoted at 39 on the front face of bar 35 and the vertical arms 37 are deflected to pass above the fulcrum bar and are of materially greater length than the 5 horizontal arms 38 thereof. Depending from the arms 38 of the sublevers are links 40 pivoted thereto at 41 and removably connected to the key levers 42 by rivets 43 having expanded free ends, as shown in 10 Fig. 5. By this means the assembled typebars and sublevers are applied to the base and connected to the key levers by a suitable tool. The key levers are pivoted beneath the cross bar 44 at the rear of the base and 15 supported in raised position by springs 45 extending therefrom to fingers 46 carried by the base. The key board ends of the key levers are guided by the comb plate 47, depending from the cross plate 85 of the frame, 20 and are provided with the usual key caps 49.

The segment 29 also supports a universal bail 50 in position to be actuated by a shoulder upon the typebar in the usual manner, and this bail is formed with a rearward 25 depending portion 51 terminating in an elongated vertical case shifting head 52. This head coöperates with a color shift member 53 carried by the vertical arm of a vibrator lever 54, the horizontal arm 55 of which is 30 connected by a pivoted link 56 with the carrier 57 for the ribbon 58 carried by the spools 13. The lever 54 is pivoted between rearwardly extending arms 59 from the slide plate 60 mounted upon the slide block 30, as 35 shown in Fig. 3. This plate has also lateral angular pivoting brackets 61 at opposite sides thereof upon which the depending legs 63 from the ribbon carrier support 62 are pivoted. The upper portion of this support 40 is formed to provide a line finder 64 at each side of the ribbon carrier which is slidably mounted in the support by means of the lugs 65 which permit free ribbon vibration. The support and carrier are normally pressed 45 toward the platen by means of a spring 66 interposed between the support and segment and such movement limited by a keeper 24 carried by the segment, see Fig. 2. The slide plate 60 is given its vertical 50 movement for case shifting through an arm 67 carried by the rock shaft 68 pivoted in the machine frame. The free end of this arm is bifurcated at 69 and engages a loop 70 at the lower portion of the slide plate. The 55 rock shaft is also provided with a rearward arm 71 pivotally connected with the shift rod 21 for actuating the latter. This shaft is rocked by means of a depending finger 72 adapted to be engaged by a hooked member 60 73 carried by a shift lever 74 mounted similarly to the key levers before described. This construction provides for a downward movement of the shift rod and an upward movement of the ribbon carrier support in 65 the case shifting operation. The parts just

described for case shifting and ribbon vibration are not specifically claimed herein as they are the subject of a separate application filed by me February 14, 1920, Serial No. 358,593 for case shift mechanism. 70

In order to permit the convenient assembling of the top plate carrying the escapement mechanism into coöperative relation with the universal bail, the latter is provided with rearwardly extending actuating arms 75 75 having open sockets 76 at their free ends which embrace pins 77 carried by uprights 78 from the rocking escapement yoke 79. This yoke is pivoted from the housing 15 as at 80 and carries the fixed dog 81 and 80 movable dog 82 coöperating with the escapement wheel 83, while the yoke is restored to its initial position by a tension spring 84 extending therefrom to the housing. The bail is supported to reciprocate in a horizontal plane by the hanger links 86 depending from the segment and restored to its rest position by a spring 87 on these links which relieves the yoke from the pressure thereof. The yoke is also assembled in detachable 90 relation to the space bar mechanism by a depending finger 88 which contacts with a rock arm 89 carried by the rock shaft 90 mounted in the base frame. This shaft is provided with the usual levers 91 extending 95 to the space bar 92 and with a vertical arm 93 from which a restoring spring 94 extends to the base frame. These parts are specifically disclosed and claimed in my application filed February 14, 1920, Serial No. 100 358,591 for escapement mechanism.

The operation of the invention will be apparent from the foregoing description and it presents an improved typebar action particularly adapted for the type of front strike 105 typewriter shown in this application. This four-part action secures the advantages of reduced leverage and accelerated stroke at the typebar connection and a direct downward pull through the link connection between the sublever and key lever which materially reduces friction at this point and provides a quick and easy action in the operation of the machine. The mounting of the typebars and sublevers upon the detachable fulcrum unit facilitates a convenient assemblage of the parts and insures a proper relation of these parts at all times. This unit also carries the universal bail and ribbon vibrator which may be thus assembled in 110 operative relation before insertion in the machine and the top unit carrying the escapement mechanism subsequently applied to detachably connect such mechanism with the bail for actuation thereby. Such application of the top unit also brings the escapement into detachable coöperative relation with the space bar mechanism carried by the base frame of the machine. This arrangement of the typebar action provides space 115 120 125 130

- above the key levers on the base frame for the disposition of the case shifting unit, space bar unit and other mechanism. In the assembling of the machine these parts may be 5 arranged upon the base and the fulcrum unit carrying coöperating members subsequently applied and the parts connected while they are readily accessible for that purpose. The top unit may then be applied to bring the 10 escapement mechanism into coöperative relation with the universal bail and space bar mechanism. The invention provides a single unit carrying the typebars and their sub-levers, the universal bail, and the ribbon 15 vibrator mounted for case shifting movement thereon. In the typebar action it will be noted that the pivots of the typebars and sublevers are in substantially the same vertical plane while the vertical arm of the 20 latter extends rearwardly when at rest and during the stroke travels forward until it reaches substantially the vertical plane of the link connection with the key lever when the typebar is at the printing point. This 25 travel in an arc for substantially equal distances above the vertical plane of the sublever pivot effects a smooth and easy movement of the typebar and avoids resistance in the returning or retracting travel thereof.
- 30 This invention presents a simple, efficient and economically constructed mechanism for the typebar action and the ready and convenient assemblage of the units of a typewriter. While the details of the invention 35 have been specifically shown and described, still it is not confined thereto as changes and alterations may be made therein without departing from the spirit of the invention.
- What I claim is—
- 40 1. In a typewriter, a frame, a key lever pivoted at the rear thereof, a typebar action unit comprising a detachable fulcrum bar secured upon said frame above and intermediate the ends of said key lever, a segment 45 supported from said bar, a sublever pivoted upon said bar, a link pivoted to said sublever and connected to the key lever by an inserted pivot, and a typebar upon said segment connected to said sublever.
- 50 2. In a typewriter, a frame, a key lever pivoted at the rear adjacent the base thereof, a detachable fulcrum bar mounted upon said frame above and intermediate the ends of said key lever, a segment supported from 55 said bar in substantially the vertical plane thereof, a sublever pivoted upon said bar, a vertically disposed link pivoted to said sub and key levers, and a typebar upon said segment having a pin and slot connection 60 with the sublever.
3. In a typewriter, a frame, a key lever pivoted thereon, a horizontal fulcrum bar unit extending across said frame above said key lever, a sublever mounted upon said 65 bar and connected to the key lever, a seg-
- ment supported in a vertical plane from said bar, a typebar mounted in said segment and connected to said sublever, a case shifting member mounted upon the frame above the key lever, and a ribbon support slidably 70 mounted upon said fulcrum bar and detachably connected to said member.
4. In a typewriter, a frame, a key lever pivoted thereon at its rear, a horizontal fulcrum bar unit extending across the frame 75 above and intermediate the ends of said key lever, a sublever mounted upon said bar and connected to said key lever, a segment supported by said bar, a typebar mounted on said segment and connected to said sublever, 80 a case shifting member mounted upon the frame above the rear of said key lever, a slide block carried by said fulcrum bar, and a ribbon support slidably mounted upon said block and connected to said member. 85
5. In a typewriter, a frame, a horizontal fulcrum bar unit provided with vertical standards, a segment mounted upon said standards at the front of said bar, a typebar mounted upon said segment, a sublever upon 90 said fulcrum bar, a key lever mounted beneath the fulcrum bar, a ribbon vibrating member carried by a support upon the rear of said fulcrum bar, and means upon the frame at the rear of said bar for shifting 95 said member thereon.
6. In a typewriter, a base frame provided with key levers and having lugs at opposite sides, a horizontal fulcrum bar rigidly secured to said lugs, sublevers mounted upon 100 said bar, vertical uprights from said bar, and a segment carried by said uprights and provided with typebars.
7. In a typewriter, a base frame provided with key levers, a U-shaped unit detachably 105 secured upon said base and comprising a horizontal fulcrum bar and opposite vertical standards, a segment mounted upon said standards and provided with typebars, and sublevers upon the fulcrum bar connected 110 to said typebars and key levers.
8. In a typewriter, a frame, a top plate having an escapement mechanism mounted upon the under face thereof, a typebar actuated universal bail supported from the 115 frame, an arm from said bail to actuate said escapement mechanism, a ribbon vibrator upon the frame beneath said escapement, and a depending arm from said bail extended beneath the escapement to actuate 120 said vibrator.
9. In a typewriter, a frame, a top plate having an escapement mechanism mounted upon the under face thereof, a fulcrum unit secured to the frame and carrying a typebar 125 actuated universal bail, an arm from said bail detachably connected to said escapement mechanism, a ribbon vibrator mounted upon the fulcrum unit, means upon the frame base beneath the vibrator for case 130

shifting the same, and a depending arm from said bail having a vertical head disposed to actuate and permit case shifting of said vibrator.

5 10. In a typewriter, a base unit provided with key levers, a fulcrum unit mounted thereon and provided with sublevers, typebars and a universal bail disposed to be actuated thereby, and a top unit carrying an 10 escapement mechanism upon its under face adapted to be assembled in detachable relation to said universal bail for actuation thereby.

11. In a typewriter, a base unit provided 15 with key levers, a fulcrum unit mounted thereon and provided with sublevers, typebars and a universal bail disposed to be actuated thereby, a space bar unit carried by said base unit, and a top unit carrying an

20 escapement mechanism adapted to be assembled in detachable relation to said universal bail and space bar unit for independent actuation by either thereof.

12. In a typewriter, a base unit provided 25 with key levers, a fulcrum unit mounted thereon and provided with sublevers, type-

bars and a universal bail disposed to be actuated thereby, a case shifting unit carried by said base, a ribbon vibrator unit mounted upon said fulcrum unit and detachably 30 connected to said case shifting unit, and a top unit carrying an escapement mechanism disposed for detachable connection with said universal bail.

13. In a typewriter, a base unit carrying 35 key levers and a case shifting unit, a fulcrum unit carrying typebars, sublevers, universal bail, and shiftably mounted ribbon vibrator disposed to be actuated by said case shifting unit, a top plate provided with an 40 escapement mechanism disposed to be actuated by said universal bail, a carriage upon said top plate having a case shifting platen, and connections from said platen to said case shifting unit.

14. In a typewriter, a fulcrum unit comprising a horizontal bar having uprights at its opposite ends, lever pivoting means upon one face thereof, and a slide block upon the opposite face thereof.

In testimony whereof I affix my signature.

CHARLES SPIRO.
